UNITED STATES PATENT OFFICE

AUBURN E. WRIGHT, OF NAPPANEE, INDIANA

SEWER-PIPE CLEANER

Application filed November 7, 1928. Serial No. 317,741.

The present invention relates to pipe cleaners and more particularly to devices of this character adapted for the cleaning of sewer pipes. One of the important objects of the invention is to provide a pipe cleaner of this character of a double ended construction whereby to enable the same to be drawn forwardly and backwardly through the pipe during the cleaning operation for effecting the cleaning of the pipe during movement thereof in both directions.

A further object of the invention is to provide means for adjusting the device for the cleaning of pipes of various diameters.

A still further object is to provide a device of this character embodying a plurality of substantially spirally shaped cleaning knives pivotally connected to each other intermediate their ends and with each pair of knives pivotally connected at their ends to the adjacent pair of knives and arranging said knives concentrically about an adjusting screw whereby to adjust the knives radially into a desired position for scraping the walls of the pipe.

A still further object is to provide a device of this character which embodies simplicity of construction, durability, which may be manufactured at a relatively low cost and otherwise well adapted for the purposes for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

Figure 1 is a side elevational view,

Figure 2 is a transverse sectional view taken substantially along a line 2--2 of Figure 1,

Figure 3 is a side elevational view showing the device in collapsed position,

Figure 4 is a plan view of one of the knives,

Figure 5 is a fragmentary detail of one end of the pivotally connected cutting blades, 50 with parts broken away and shown in sec-

tion and illustrating a modified form of guide shoe for the ends of the knives, and

Figure 6 is a detail of the swivel connector provided for attaching a pulling cable to the ends of the various knives.

Referring now to the drawings in detail, wherein for the purpose of illustration I have disclosed a preferred embodiment of my invention, the numeral 5 designates an adjusting screw oppositely threaded at the ends 60 and upon each of the oppositely threaded portions of which is arranged an adjusting spider 6.

Each of the spiders are adapted for longitudinal adjustment on the respective ends of the screw and each spider is provided at its outer edge with a plurality of pairs of spaced apart lugs 7 between which the inner ends of arms 8 are disposed for pivotal connection thereto by pins 9.

The outer ends of the arms 8 are adapted to swing outwardly from a position longitudinally with respect to the screw into a position radially thereof and are arranged with their outer ends disposed between pairs of spaced parallel lugs 10 for pivotal connection thereto by pins 11. Each pair of lugs 10 are cast integrally and are formed with a shank 12 extending through openings formed in the crossed ends of cutting blades 13 and with the outer end of the shank hammered into a head 14 for retaining the ends of the blade 13 upon the shank for pivotal movement.

The outer end of the shank 12 is reduced as shown at 15 so that the diameter of the head 14 will not exceed the diameter of the inner end of the shank 12, as clearly illustrated in Figure 5 of the drawing and a retaining washer 16 is interposed between the heads 14 and the outermost blade 13 in order to prevent withdrawal of the head of the shank from said blade.

The respective blades 13 are connected to each other in a manner similar to the connection of the arms of a lazy tong, the cross blades being pivotally connected to each other as indicated at 17 and arranged concentrically about the screw 5.

The forward edge of each of the blades 100

13 are formed with teeth 18 to facilitate the cutting of objects with which the blades come into contact. One of the blades extends slightly beyond its pivoted end, as shown at 19 and is provided with an opening for receiving a ring 20 whereby to attach a chain section 21. The projected end 19 of the blade is also bent inwardly to facilitate the riding of the end thereof over the seams of the pipe through which the cleaner is being drawn.

10 The chains 21 at each end of the cleaner are attached to a swivel coupling 22 composed of a pair of ring members 23 swivelly connected to each other by a pin 24, one of the rings 23 being provided for attaching the ends of the chain 21 thereto and the other of said rings being provided for attaching a pulling chain or cable by means of which the cleaner is drawn through the sewer pipe.

15 Each of the blades 13, adjacent one end thereof are provided with hooks 25 disposed inwardly of the blade for engaging obstacles encountered in the pipe, such as twigs or the like during the movement of the cleaner in one direction.

20 It will be apparent from the foregoing that the cleaner is of a double ended construction so that the cleaning action will be produced while drawing the device forwardly and backwardly through the pipe.

25 In order to prevent engagement of the ends of the blade with the seams of the pipe an arcuate shoe 26 is provided having one end extended beyond the projected end 19 of the blade and curved inwardly toward the center of the cleaner. The inner face of the shoe 26 is formed with a recess 27 for receiving the head 14 and washer 16 and thus to form a cover for the same so as to protect the head and prevent the wearing down of the same during the frictional engagement of the cleaner with the walls of the pipe.

30 The shoe is secured to the blades 13 by means of rivets 28 or the like. The ends of the screw 5 are constructed of a non-circular formation as shown at 28 for the purpose of receiving a wrench or other tool in order to provide for the adjustment of the screw for the purpose of expanding or contracting the blades 13. Through this adjustment it will be apparent that the diameter of the cleaner may be increased or decreased as desired to provide for the cleaning of pipes of various sizes.

35 In the operation of the cleaner it will be apparent that the same may be drawn forwardly and backwardly through the pipe and upon the engagement of the blades of the cleaner with branches, roots or similar obstacles within the pipe that the same not only will be drawn through the pipe with the cleaner but by reason of the toothed edges of the blades, such obstacles will be cut into smaller pieces and thus facilitate the removal thereof from the pipe.

It is obvious that my invention is susceptible to various changes and modifications in construction without departing from the spirit of the invention or the scope of the appended claims, and I accordingly claim all such forms of the device to which I am entitled.

Having thus described my invention, what I claim as new is:

1. A pipe cleaner of the class described comprising a screw oppositely threaded at its ends and having spiders mounted thereon for opposite longitudinal adjustment on the screw, arms pivotally attached at one end to said spiders, blades pivotally attached to the opposite ends of said arms, and connected at their ends to each other in concentric relation about the screw, said spiders being operable to expand and contract the blades with respect to the screw and chains attached at the opposite ends of said blades for drawing the cleaner through the pipe in opposite directions, said blades being pivotally connected to each other intermediate their ends in pairs with the ends of each pair of blades disposed in cooperative cutting relation. 75

2. A pipe cleaner of the class described comprising a screw having oppositely threaded ends, spiders adjustably mounted on the ends of the screw and adapted for movement in opposite directions, a plurality of arms pivotally attached at one end to said spiders, a plurality of blades connected to each other in a cylindrical lazy tong formation disposed concentrically about said screw, means for pivotally connecting the outer ends of said arms to the ends of said blades, hooks on the inner side of said blades and chains attached at the opposite ends of the blades for drawing the cleaner through the pipe in opposite directions. 95

3. A pipe cleaner of the class described comprising a screw oppositely threaded at its ends, a spider adjustably mounted on each end of the screw, a plurality of arms pivotally attached at one end to each of said spiders, a plurality of blades connected to each other in a cylindrical lazy tong formation disposed concentrically about said screw, lugs disposed at the outer ends of said blades providing a pivotal connection for the outer end of said arms, said lugs having a shank extending through the blades for the pivotal connection of the ends thereof, a head formed on the shank disposed outwardly of the blades for securing the blades to each other, chains attached to the opposite ends of the blades for drawing the cleaner in opposite directions through the pipe and shoes secured to the pivoted ends of said blades having their outer ends turned inwardly and having recesses formed on their inner faces for receiving the head of said shank whereby to protect the same against contact with the walls of the 110 115 120 125 130 pipe.

pipe during the movement of the cleaner therethrough.

4. A pipe cleaner of the class described comprising a screw oppositely threaded at its ends and having spiders mounted thereon for opposite longitudinal adjustment of the screw, blades arranged in pairs with the blades of each pair pivotally connected to each other and having their respective ends disposed in cooperative cutting relation, pivot members connecting the ends of each pair of blades to an adjacent pair of blades and arms extending from the spiders having their outer ends also pivotally connected to said pivot members for pivotally connecting the opposite ends of each of the blades to the spiders.

5. A pipe cleaner of the class described comprising a screw oppositely threaded at its ends, spiders mounted thereon for opposite longitudinal adjustment on the screw, blades arranged concentrically about said spiders in pairs with each pair of blades pivotally connected intermediate their ends and having their ends disposed in cooperative cutting relation, means pivotally connecting each end of each blade to an end of one adjacent blade and including a pivot pin having one end projecting beyond the plane of the blades and formed with a head, shoes secured to the ends of the blades and covering the heads of said pins for protecting said heads from wear and means pivotally connecting the ends of the blades to the spiders.

- 35 In testimony whereof I affix my signature.
AUBURN E. WRIGHT.
